Atty.

UNITED STATES PATENT OFFICE.

MILTON K. NOAKER, OF AKRON, OHIO, ASSIGNOR TO THE AKRON CULTIVATOR COMPANY, OF SAME PLACE.

SPRING CULTIVATOR-HOE.

SPECIFICATION forming part of Letters Patent No. 660,276, dated October 23, 1900.

Application filed July 18, 1900. Serial No. 23,992. (No model.)

To all whom it may concern:

Be it known that I, MILTON K. NOAKER, a citizen of the United States, residing at Akron, in the county of Summit and State of Ohio, 5 have invented a certain new and useful Improvement in Spring Cultivator-Hoes, of which the following is a specification.

My invention has relation to improvements in that class of cultivators that by means of 10 a spring and connected mechanism are held with sufficient rigidity to dig and move the earth, but are so arranged that they will yield on encountering a firm resistance, as a stone or root, and thus avoid breaking the machine, 15 and will assume their position on passing the obstacle.

The object of my invention is to produce a new and improved article of the class designated that shall be simple in construction, 20 efficient in operation, and in which the angle of the yielding joint shall have means for adjustment to adapt the hoe to soils of different degrees of firmness.

To the aforesaid objects my invention consists in the peculiar and novel construction, 25 arrangement, and combination of parts hereinafter described, and then specifically pointed out in the claim, reference being had to the accompanying drawings, forming a part 30 of this specification.

In the accompanying drawings, in which similar reference-numerals indicate like parts in the different views, Figure 1 is a side elevation of my improved cultivator-hoe in its 35 normal position, and Fig. 2 a like view showing the hoe yielding to pass an obstacle.

Referring to the figures, 1 is the draw-bar, which is of I-bar steel, of a common form of construction, to which is securely attached 40 an inclosing plate 2, having a rearwardly-extending arm that has a cup 3 to hold the lower end of a spiral spring 4 and a downwardly-projecting lug 5 to afford a support for the fulcrum-pivot 6.

45 The hoe-blade 7 is adjustably secured to a shank 8, extending from an inclosing extension 9, pivotally connected with the lower end of the draw-bar 1. The extension 9 has rearwardly-projecting lugs 10, in which is 50 pivotally mounted a short connecting-rod 11, with its upper end pivotally connected with

a lever 12, pivoted on the lug 5. The opposite half of the lever 12 is pivotally connected with a bolt 13, that passes through the spring 4 and bears at its upper end a cap that rests 55 on the spring and is secured by a nut. The lever 12 has a short plate 14, extending at a slight angle therewith, in which is fitted to turn a screw-threaded bolt 15, that bears against the rearwardly-extended arm of the 60 plate 2 for the purpose of adjustment. At the top front of the extension 9 the metal is extended to form a stop 16 to encounter the front of the bar 1 and prevent the top rocking backward.

65 In operation the parts stand normally in the position shown in Fig. 1, with the extension 9 and its shank in alinement with the lower end of the draw-bar. The connecting-rod 11 and lever 12 are slightly bent to the 70 front at their joint, the degree of departure from a true line of these parts being regulated, as before stated, by the bolt 15, so that the parts will retain their position against ordinary resistance. When the hoe encounters an obstacle offering resistance that might break the parts, the joint between the rod 11 and lever 12 yields and allows the hoe to swing 75 backward, as shown in Fig. 2, until the obstacle is passed.

80 Having thus described my invention, what I claim, and desire to secure by Letters Patent, is—

In a spring cultivator-hoe, the combination with the draw-bar, of a rearwardly-extending 85 arm adapted to support a coiled spring, a spring mounted thereon a rod within said spring adapted to compress the same and connected with one end of a pivoted lever, a shovel-bearing extension pivoted to rock 90 backward, a rod connecting said extension and the opposite end of said lever, and an adjusting-screw to regulate the angle between said lever and rod, substantially as shown and described.

95 In testimony that I claim the above I hereunto set my hand in the presence of two subscribing witnesses.

MILTON K. NOAKER.

In presence of—

C. E. HUMPHREY,
C. P. HUMPHREY.
